Attorney.

UNITED STATES PATENT OFFICE.

PAUL LUCAS, OF BERLIN-FRIEDENAU, GERMANY.

VAPOR LAMP, ESPECIALLY HYDROCARBON INCANDESCENCE LAMP.

Application filed May 10, 1922. Serial No. 559,821.

To all whom it may concern:

Be it known that I, PAUL LUCAS, a citizen of the German Republic, and a resident of Berlin-Friedenau, Germany, have invented 5 a certain new and useful Improved Vapor Lamp, Especially Hydrocarbon Incandescence Lamp, of which the following is a specification.

This invention relates to a wickless lamp 10 which is to be fed with petroleum or another hydrocarbon and is intended for use especially as incandescence lamp, and in which the fuel is conducted to the evaporator or gasifier by means of compressed air.

15 The invention consists partly in the feature that a piston which produces the compressed air and is subjected to the pressure of a spring is located in a vertical cylinder, above which the fuel receptacle and a chamber for compressed air are arranged; the piston is moved upwards in that cylinder under the pressure of said spring which is located below it. Another part of the invention consists in a certain combination and 20 arrangement of parts which renders possible in an easy manner the assembling and taking to pieces the spring-actuated pump composed of the cylinder, the piston and the 25 spring.

30 A third part of the invention consists in a special construction of the gasifier tube and of the burner nozzle, the object being, that the burner proper may be easily removed and the gasifier tube may be easily 35 cleaned.

A fourth part of the invention consists 40 in certain means, the object of which is, in the case of the lamp failing or extinguishing, to prevent the further acting pressure of the air from injuring the lamp, as is all 45 fully described hereinafter.

In order to make my invention more clear, I refer to the accompanying drawing, in which similar numbers of reference denote 50 similar parts throughout the several views and in which Fig. 1 is a vertical section through a lamp constructed according to this invention and shown by way of example. Fig. 2 is a horizontal section through the 55 lamp standard or the cylinder respectively, in line 2—2 of Fig. 1. Fig. 3 is a vertical section through the burner proper, drawn on a larger scale.

The cylindrical standard 5 is affixed at its 55 lower end to the foot 1 and carries at its

upper end the basin 10. The standard or cylinder 5 encloses a piston 4 which is attached to a tube 3 adapted to be displaced along a tube 2 supported by a transverse bar 9. Within the tubes 2 and 3 is a spiral 60 spring 6 which has comparatively many convolutions, say 60, and tends constantly to move the piston 4 upwards. Owing to the spring having that comparatively large number of convolutions, its pressure along 65 the required length of way is practically uniform.

7 is a transverse bar which is affixed to the tube 3 and the ends of which extend through vertical slots 8 of the cylinder 5. 70 The piston 4 is withdrawn and the spring is compressed by shoving the bar downwards in the slots 8. Displacing the piston in the direction to the basin 10 is effected by the spring. The displacement proceeds gradually corresponding to the fall of the liquid level in the basin.

The bar 9 is loosely put through suitable slots provided in the cylinder 5, and serves as support for the tube 2 and the spring 6. 80 To take the inner parts of the pump to pieces for the purpose of inspecting or cleaning it, nothing else is necessary but to remove the bar 9, when the parts 2, 3, 4, 6 may be easily removed.

The compressed air enclosed in the upper portion of the cylinder 5 is conducted by a tube 13 into the basin 10. The tube 13 is provided with a non-return valve 14. Owing to the pressure of the air upon the petrol, etc., contained in the basin 10, a certain quantity of the liquid fuel is driven upwards into and within the gasifying tube 11 which has at its top a nozzle 12. The tube 11 consists of German silver or of another material that is a comparatively bad conductor of heat so that the basin is but moderately heated. The upper end of the tube 11 is slightly conical and encompassed by a correspondingly shaped sleeve 15 which 90 consists of copper or another material that is a good conductor of heat. The sleeve 15 is surrounded by the usual known heating or starting basin 16.

The sleeve 15 carries the burner proper 105 and may be easily taken off the tube 11, together, of course, with the burner. Also the nozzle 12 is removable from the tube 11. The gasifying tube is, thus, easily accessible for inspection and cleaning.

If a lamp of the kind in question extinguishes the liquid fuel continues to escape from the nozzle (12) under the pressure of the spring 6 and flows down upon the lower parts of the lamp. To obviate such an occurrence, the basin is subdivided by a horizontal wall 27 (Fig. 1), whereby the basin is subdivided into two compartments, of which the lower (10) contains the liquid fuel, whereas the upper (17) serves to intercept and collect the non-consumed fuel that may have escaped from the nozzle 12.

The burner proper consists of three concentric tubes 20, 21, 18 of which the first receives the gas issuing from the nozzle 12 and has at its top a perforated or wire gauze cap 22. The resistance of this cap is such that the mixture of fuel gas and air passing upwards within the tube 20 is throttled in such a measure that a certain portion passes downwards through the tube-like space between the tubes 20 and 21. These tubes join at their lower ends the outer tube 18 where there are holes 19 through which the mixture portion in question escapes and forms a plurality of auxiliary flames.

A portion of the fuel-air-mixture may be conducted over into the space between the tubes 20 and 21 also before getting to the top 30 of the tube 21, viz, by means of an inverted U-shaped traverse-piece 24 (Fig. 3) which is inserted into lateral apertures 25 of the tube 20 and forms a channel 26 which intercepts a portion of said mixture and conducts it laterally away into said space, as indicated by the arrows in Fig. 3.

At the lower end of the burner tube 18 is a small cap 23 which consists of a good conductor of heat, such as brass, copper, or 40 the like, and conducts part of the heat of the auxiliary flames burning at the apertures 19 to the sleeve 15 in order to assist in the gasification of the fuel.

Owing to the draught caused by the chimney the auxiliary flames at the apertures 19 are directed upwards. Supposing, the lamp has got extinguished from any cause and the main flame (at 22) is again ignited, then the small currents of the fuel-air-mixture 50 escaping through the apertures 19 and passing upwards will automatically ignite at that main-flame.

A lamp of the novel construction offers material advantages over the older ones. 55 Making the lamp operate is greatly facilitated by the provision of the air-pump in the lamp foot, especially in contradistinction to the so-called moderateur-lamps. To start the lamp, the piston 4 is drawn downwards with aid of the projecting ends of the horizontal rod or handle 7 so that air enters into the space above it. There are no motion-transmitting means whatever, no rolls, rails, systems of levers, or the like. 60 The piston is actuated quite directly in its

axial direction, in the simplest manner imaginable. After that, the piston is uniformly lifted by the pressure of the appropriately chosen spiral spring 6. The dimensions, at least in the example illustrated 70 in the drawing, are so chosen that one downward movement of the piston suffices for making the lamp burn 6 hours. By the position of height of the bar 7 is to be seen when another downward movement of the 75 piston is necessary.

Having now described my invention, what I claim as new and desire to secure by Letters Patent of the United States is:

1. In a vapor-lamp, especially a hydro-carbon incandescence lamp, the combination with a closed fuel-basin, a burner over it, and a gasifier between the basin and the burner, of an air-cylinder with a piston located below said basin, and moving upwards 80 when forcing air into said basin, and rigid means for actuating the piston from the outside of the cylinder and projecting through slots thereof, as set forth.

2. In a vapor-lamp especially a hydro-carbon incandescence lamp, the combination with a closed fuel-basin, a burner over it, and a gasifier between the basin and the burner of a vertical air-pump cylinder located below said basin; a piston located 90 within that cylinder and moving upwards when forcing air thereinto; a hollow piston rod affixed to the piston; a stationary guide-tube for the piston-rod; a spiral spring located within said piston rod and its guide 95 tube; rigid means for actuating the said piston and projecting through vertical slots of said cylinder; and a removable support for the lower end of the said guide-tube as set forth.

3. In a vapor-lamp, especially a hydro-carbon incandescence lamp, the combination with a closed fuel-basin; a gasifier arranged upon it and having a slightly conical upper end; a burner having a correspondingly shaped lower end with which it is attached to the gasifier of a vertical air-pump located below said basin, and rigid means for actuating the piston of that pump from the outer side of the pump-cylinder and projecting through lateral slots thereof, as set forth.

4. In a vapor-lamp, especially a hydro-carbon incandescence lamp, the combination with a closed fuel-basin with a horizontal partition wall subdividing it into a closed 110 lower liquid fuel compartment and an upper collecting receptacle for overflowing fuel; a gasifier upon said basin and a burner upon said gasifier, of a vertical air-pump located below said basin, and means for actuating the piston of that pump from the outer side of the pump-cylinder, as set forth.

5. In a vapor-lamp, especially a hydro-carbon incandescence lamp, the combination with a closed fuel-basin, a gasifying tube 120

extending upwards from said basin, a burner composed of three concentric tubes, of which the outermost has apertures at its lower end and the other two form a passage from the 5 burner head to said apertures, and a small basin which surrounds the said apertures and is open at its top and consists of a good

conductor of heat, of a vertical air-pump located below said basin, and means for actuating the piston of that pump from the 10 outer side of the pump-cylinder as set forth.

In testimony whereof I affix my signature.

PAUL LUCAS.
